UNITED STATES PATENT OFFICE.

CYRUS HOWARD HAPGOOD, OF NUTLEY, AND GEORGE FREEBORN MAYNO, OF EAST ORANGE, NEW JERSEY, ASSIGNEES TO THE DE LAVAL SEPARATOR COMPANY, OF NEW YORK, N. Y., A CORPORATION OF NEW JERSEY.

PROCESS FOR REFINING VEGETABLE OILS.

Application filed June 29, 1921. Serial No. 481,396.

To all whom it may concern:

Be it known that we, CYRUS HOWARD HAPGOOD and GEORGE FREEBORN MAYNO, citizens of the United States, residing at Nutley and 5 East Orange, respectively, county of Essex and State of New Jersey, have invented a new and useful Improvement in Processes for Refining Vegetable Oils, of which the following is a full, clear, and exact description, reference being had to the accompanying drawings, which form a part of this specification.

The object of our invention is the refinement of vegetable oils. The invention is 15 especially applicable to cottonseed oil, but is also applicable to any other vegetable oil containing impurities more readily saponifiable than the oil itself.

It is known to treat cottonseed oil with 20 an alkali for the purpose of saponifying the fatty acid impurities in the oil and to then separate the oil from the soaps. One difficulty arises from the circumstance that while the fatty acids are more readily saponifiable than the oil, the oil itself is also saponifiable and hence there goes into soap stock a considerable proportion of the oil, both combined and free. As a constituent part of a soap stock the oil has ordinarily much less commercial value than when it is recovered as 30 pure oil. It is recognized that it is desirable to so limit the duration of treatment with alkali and the strength of the alkali solution as to saponify only the fatty acids and avoid 35 saponification of the oil, but the desideratum has not been achieved, nor is its attainment, in any absolute degree, practicable.

The more specific object of our invention is to so treat the oil that the amount of oil 40 that goes into soap stock will be reduced to a minimum. Another object of the invention is to materially increase the amount of oil that can be treated within a given time. Another object of the invention is to so preliminarily treat the oil that it will be deprived of husks, dirt, etc., before the oil is 45 subjected to the treatment for removal of the readily saponifiable impurities. Another object of the invention is to combine our improved treatment for saponifying the fatty acids and eliminating the resultant soap with a final treatment adapted to complete clarification.

A valuable feature of our improved proc-

ess consists in the fact that the operation 55 preceding the final clarification treatment is a continuous operation as distinguished from a batch operation and that only a small quantity of oil, at any given time, is being subjected to the saponifying and separating 60 treatment.

The process is not dependent for its execution on any particular apparatus, but we have shown, in the drawings, a diagram of 65 an apparatus adapted to carry out our process. The separate contrivances of which the apparatus is composed are individually old, although they have not heretofore been associated together in the combination or sequence illustrated.

a represents a source of supply for 70 crude oil, say a tank car. The tank car is connected, by a valved pipe *b*, with a rotary drum filter or screen *c*, the meshes of which are fine enough to prevent the 75 passage through the screen of husks, shells, coarse dirt or other solid or flaky impurities that the crude oil may contain. The oil, with (usually) some fine dirt in suspension, passes through the screen into a trough 80 *d*, from which the oil flows into a tank *e* which is of relatively large capacity, say an eight thousand gallon tank. This tank is provided with heating coils *f* to maintain the body of oil at a temperature at which it will 85 be capable of flowing. It is customary to heat the oil, prior to treatment with alkali, to a temperature approximating 140 degrees F. in order to enable the oil, when treated in a large batch, to readily flow and 90 mix with the alkali. It is possible, in our process, to heat the oil to a high temperature, but such high heat treatment is very undesirable in that in our process, an emulsion 95 would be formed that would be difficult to break. We have found it possible to avoid heating the oil substantially above eighty degrees F., because in our process extreme fluidity is unnecessary. We thus avoid the production of a substantial emulsion. The 100 lower the temperature, the less of an emulsion will be formed and we therefore prefer a range of temperature between eighty and one hundred degrees F. with a decided preference for the lower limit of such range.

g represents a tank for caustic soda or other alkali or saponifying agent. This tank is of much smaller capacity than the oil

tank *e*, as the amount of alkali solution required to treat a given quantity of oil is only (say) about eight per cent of the oil. The capacity of the alkali tank may therefore be about six hundred and forty gallons.

From the tanks *e* and *g* lead valved pipes *h* and *i* to a funnel *j* communicating a mixer *k*. This mixer is of such size and the outflow therefrom is so regulated that the mixture 10 of oil and alkali will flow through it in about eight or ten minutes. The duration of treatment, however, may vary from five to fifteen minutes or even within a somewhat wider range of time. The mixer contains fixed and 15 rotatable elements whereby the oil and alkali are subjected to mechanical agitation so as to effect a primary saponification of the fatty acids.

From the mixer *k* the mixture flows to a 20 centrifugal separator *m*, which preferably is of the type shown in the Snyder Patent No. 1,283,343, dated October 29, 1918. In the separator there is a transitory stage of further admixing which, while of very short 25 duration, occurs while the mixture is finely broken up, thereby allowing an intimate contact of free alkali with the fine fatty acid particles. The heavy alkali and soap stock (which at this stage is in a very fine "break" 30 or separated condition) moves outward to the periphery, displacing the lighter oil inwardly, the oil being "floated" off through discharge spout *n* and the heavier ingredients discharging through the sludge spout *o* into 35 a pipe *p* leading to a soap stock receptacle (not shown). The soap stock comprises chiefly combined alkali and fatty acid and contains very little oil either in combined or free form.

40 The oil, which is practically free of soap, is discharged into a pipe *s* leading to a tank *t*, which preferably has a capacity about equal to that of the oil tank *e*. To this tank is added an inert substance adapted to act 45 as a clarifying or bleaching agent, such as fuller's earth. When the entire volume of oil in the tank *e* has been treated as described (or during the inflow of the oil into the tank *t*), a shaft, carrying the blades *u*, 50 is kept in rotation so as to thoroughly mix the fuller's earth with the oil. The mixture is then forced, by means of a pump *v*, into a filter press *w*, from which the perfectly clarified oil is discharged into a pure oil 55 reservoir *x*.

It will be understood that in the drawing the relative size of the centrifugal separator is considerably exaggerated.

The percentage and strength of the caustic 60 alkali employed in the process depends on the grade of crude oil being treated. With a prime crude oil containing from .8 to 2 per cent. free fatty acid, caustic alkali of six or seven per cent of ten degrees Baumé can 65 be used successfully. With oils of poorer

quality and higher in fatty acid an alkali of a stronger degree and higher percentage must be used. The percentage of fuller's earth may be about one-fourth of one per cent. 70

Having now fully described our invention, what we claim and desire to protect by Letters Patent is:

1. A continuous process for refining vegetable oils which comprises filtering out 75 the coarser solid particles, subjecting the same to a temperature of not less than approximately eighty degrees F. and not higher than one hundred degrees F., flowing a stream of a saponifying agent into contact with a flowing stream of said heated oil and subjecting the mixture during the flow to a mechanical mixing action to effect a primary saponification of the fatty acids, subjecting the flowing mixture to centrifugal 85 force, thereby effecting a relatively very short but more intimate admixture of the constituents with a resultant secondary saponification of the fatty acids followed by separation of the saponifying agent and soaps from the oil, agitating the oil with an inert clarifying agent and filtering the oil. 90

2. A continuous process for refining vegetable oils which comprises flowing a 95 stream of a saponifying agent into contact with a flowing stream of oil, subjecting the mixture during the flow to a mechanical mixing action in such small quantity and for so short a time as to effect a primary 100 saponification of the fatty acids without saponification of a substantial proportion of the free oil, and subjecting the flowing mixture of oil and soap to centrifugal force to effect a relatively very short but more 105 intimate admixture of the constituents with a resultant secondary saponification of the fatty acids followed by separation into layers and continuously floating off the oil and discharging the soaps, thereby effecting 110 a maximum saponification of the fatty acids with a minimum saponification of oil. 110

3. A continuous process for refining vegetable oils which comprises flowing a 115 stream of a saponifying agent into contact with a flowing stream of an oil and during the flow of the mixture subjecting it to a mechanical mixing action of sufficient duration to effect a saponification of the fatty acids without saponification of a substantial 120 proportion of the free oil, and then without substantial interruption of the flow subjecting the mixture of oil and soap to centrifugal force, floating off the oil, treating the oil with an inert clarifying agent and 125 separating the oil therefrom. 120

4. A continuous process for refining vegetable oils which comprises flowing a 130 stream of oil maintained at a temperature of not less than approximately eighty degrees

- F. and not higher than approximately one hundred degrees F. and during the flow of the mixture subjecting the same first to a mechanical agitation with a saponifying agent for a time sufficient to saponify a substantial proportion of the fatty acids without saponification of a substantial proportion of the free oil, and then to centrifugal force and floating off the oil.
- 5 10 5. A continuous process for refining vegetable oils which comprises flowing a stream of oil maintained at a temperature of not less than approximately eighty degrees F. and not higher than approximately one hundred degrees F. and during the flow of the mixture subjecting the same first to a mechanical agitation with a saponifying agent for a time sufficient to saponify a substantial proportion of the fatty acids without saponification of a substantial proportion of the free oil, and then to centrifugal force, floating off the oil, treating the oil with an inert clarifying agent and separating the oil therefrom.
- 15 20 25 6. A continuous process for refining vegetable oils which comprises maintaining a body of oil and a body of a saponifying agent, flowing from each body a substantially continuous stream at a regulatable rate, mixing said streams, maintaining admixed at any given time a volume of the mixture that is small relatively to the volume of the original body of oil and for a time sufficient to saponify the fatty acids without saponification of a substantial proportion of the free oil, and practically immediately thereafter, subjecting the mixture of oil and soap to centrifugal force and floating off the oil, treating the oil with an inert clarifying agent and separating the oil therefrom.

In testimony of which invention, we have hereunto set our hands, at New York, on this 31st day of May, 1921.

CYRUS HOWARD HAPGOOD.
GEORGE FREEBORN MAYNO.
